J. C. HENDERSON.

Heating Stove.

No. 20,274.

Patented May 18, 1858.

UNITED STATES PATENT OFFICE

J. C. HENDERSON, OF ALBANY, NEW YORK.

STOVE.

Specification of Letters Patent No. 20,274, dated May 18, 1858.

To all whom it may concern:

Be it known that I, JOSEPH C. HENDERSON, of the city and county of Albany and State of New York, have invented a new and improved mode of constructing the combustion chamber of stoves, for burning bituminous coal and other fuel that by its chemical formation tends to produce much smoke and soot; and I do hereby declare that the following is a full and exact description thereof, reference being had to the accompanying drawing and to the letters of reference marked thereon.

The nature of my invention consists in the construction of a combustion chamber adapted to be applied to the common forms of fire box, or pot containing the fuel, of stoves now in use, known as "up draft stoves" which is to better adapt them for the use of these descriptions of fuel.

With my improvement, an engine of combustion is composed of three active parts, viz: first, the fuel box where primary combustion takes place; second, the combustion chamber above the fuel, where a secondary combustion is made to take place, and third, the heating chamber, or a chamber to receive from the combustion chamber, the results of combustion, and convey them to the chimney, and to serve as the heating surface of the stove, above the pot containing the fuel.

In the construction of this improvement it was assumed, that the principle applicable to the combustion of these descriptions of fuel, are: that the higher the temperature, at which combustion of the volatile combustible is to be carried on; after it rises from the incumbent fuel, the more perfect will be the combustion; and as these descriptions of fuel, under a state of ignition, tend rapidly to assume a volatile form; it is necessary to raise the temperature of the chamber, above the fuel, to a higher degree than the fire pot itself, containing the solid fuel, in a state of ignition. To produce this result, the surfaces of the secondary combustion chamber, must not be the surface of radiation; but so constructed as to retain caloric, prevent the free escape of the volatile combustible; and

consummate its combustion at a very high temperature.

The drawing represents a vertical center cross section of an ordinary stove with my improvement applied; A, the ash pan, B the grate, C C C C exterior cylinder, divided at D D, and attached by a partition to the combustion chamber G, forming the exterior heating chamber; and placed on the fuel box E.

The fuel box E when made specially for this improvement, may be made wholly of cast iron, should be made flaring, the depth the same as those in common use; varied to adapt them to the particular purpose, and quality of fuel intended to be used.

The chamber G is a frustum of a cone, but it may be made of other forms, and answer the purpose, at its base as large as the top of the fuel box E, and contracted at the top to a proper size, to produce and maintain, while in action, a plenum within the combustion chamber, constructed in this manner, and used in combination with the exterior chamber formed by cylinder C, C, and partition D D the whole inclosed by a top fitted to cylinder C, C, and placing the exit pipe below the top of chamber G, the escape of the volatile combustible from chamber G, before its combustion is consummated, is prevented.

The chamber G and the exterior heating chamber, should be at least three times as high as the depth of the fuel box E, and may be increased in height when the circumstance will admit.

The outlet of chamber G for ordinary purposes may be fixed to a definite size, but when used for large furnaces, an arrangement of valve, slide, or their equivalent, may be adopted, and used to increase or diminish the size of the outlet at pleasure.

To enable chamber G to answer a more utilizing purpose, and prevent it from burning out, it may be built with a nonconducting substance or it may be constructed wholly of fire brick or of soap stone, but for ordinary purposes it will answer the purpose, if made of substantial casting of iron.

The exterior cylinder C C forming the 100

heating chamber, may be made of any substantial material that is a good conductor of heat. Near the base of the heating chamber is placed the exit pipe P to connect with the flue, one or more may be used as required. H is the feed door, which may be made to open through the lower part of chamber G, as shown in the drawing, or it may be made to open directly into the fuel box E.

In the angle between the partition D, and the fuel box E, may be placed a flue or passage way, as shown in the drawing, opening externally at a convenient point, to admit air at b b b b to distribute and mix with the highly heated gases as they accumulate in chamber G. Air may be admitted in this manner to advantage, when the fuel box is deep, or when using a poor quality of fuel, that inclines to pack and prevent the necessary supply of air from passing up through the ash pit and grate, or when supplying fuel to a furnace that is in a highly heated state to prevent puffs and explosions, but for ordinary purposes this arrangement may be dispensed with, being of no practical use if the proportion of parts are properly adapted to each other.

The admission of air is not claimed as any part of my invention, it having often been used in a similar manner.

The utility of my invention when applied to an engine of combustion for all soft and bituminous substances must be apparent.

With the various kinds of stoves alluded to, the volatile combustible as it rises from the fuel, comes in contact with surfaces that are made cool, by the medium to be heated passing over its exterior surface, whereas, with my improved combustion chamber, as it rises from the fuel box, comes in contact with surfaces more highly heated, and being held in suspension, or as it were compressed, and held in the combustion chamber by the contracting form of its outlet, in combination with the exterior heating chamber, they are very thoroughly consumed.

In constructing and applying this improvement, the exit pipe, or pipes, should be placed at the base of the heating chamber; that the reverberation of heat upon the exterior surface of the combustion chamber, may raise the temperature within to a very high degree, thus insuring a very perfect combustion of the volatile combustible, on its passage from the fuel box to the upper part of the combustion chamber, reversing the ordinary method of burning these descriptions of fuel, by having the top of the combustion chamber, its most extremely heated part, by which arrangement that instead of having the volatile combustible leave the fuel box, for a less heated part of the combustion chamber, it may leave the fuel box where

only primary combustion takes place; for a more intensely heated part. The caloric retained by the contracting outlet of the combustion chamber acting in combination with the caloric retained by the exterior heating chamber passing the results of combustion over the exterior surface of the combustion chamber, the whole is made to conduce to the more perfect combustion of the volatile combustible, and thus a reciprocating action is kept up, heat producing heat, as combustion is made more perfect.

A very advantageous result of my invention is, that it admits of the fuel box being made without the use of any non-conducting substance, a feature very desirable on many accounts. In stoves for heating purposes it can be made of cast iron. For the generation of steam, or for hot water furnaces, the fuel may lie against a water space, as it has been found by practical use, that owing to the combustion chamber, above the fuel, being kept so extremely heated, and reflecting its heat by its combination with the exterior chamber; to the solid contained fuel, there is no difficulty in keeping up a very vivid, and good combustion within the fuel box, without its being lined with nonconducting substances; causing it (the fuel box) to radiate more heat than when used with the common form of fire chamber, the practical result being that the whole surface of the stove is a very powerful and quick heating surface.

I prefer that my improved combustion chamber be made of cylindrical form, but it may be made to conform, and be applied to most of the common forms of fire pots now in use, time and practical use, only, can determine its best mode of application.

I am aware that a tapering contracting chamber has been used for the purpose of holding the volatile combustible in suspension, over an open fuel box. I am also aware that stoves have been constructed with a cylinder standing within, and running parallel with the exterior cylinder from the bottom up; between the fuel box and the exterior casing, to near the top of the stove, for the purpose of conveying air to the sides and top of the fuel box, and to form a descending flue to discharge at the base of the stove. A stove thus constructed cannot accomplish the object of my invention. The outlet of the inner cylinder not being contracted so as to preserve a plenum within the combustion chamber, the volatile combustible readily escapes to the exterior chamber, when, coming in contact with its exterior surface, parts with its caloric, the process of combustion is checked, causing the accumulation of smoke, and soot, in the base of the stove, whatever advantages a stove of that construction may have, is wholly owing

to the descending flue, and not to the construction of the combustion chamber.

What therefore I claim as my invention, and desire to secure by Letters Patent, is—

5 The chamber G, contracted at the top, so as to produce, and maintain, while in action; a plenum within the combustion chamber; when used in combination with the exterior chamber and connected by partition D, D,

as described, for the purpose of preventing 10 the escape of the volatile combustible from the combustion chamber, before its combustion is consummated.

JOSEPH C. HENDERSON.
